8 Claims. (Cl. 198—219)

This invention relates to improvements in conveying and storing units, and refers more particularly to such units for conveying and storing pieces of circular stock, such as shafting and the like, as they pass from one machine to another during the mass production of such parts.

It is an object of the invention to provide such conveying and storing units wherein means are provided for imparting a step-by-step forward movement to workpieces placed thereon, whereby they are intermittently advanced a short distance at a time until they reach the foremost unoccupied position thereon.

Another object of the invention is to provide such a conveying and storing unit wherein means are provided for automatically re-commencing the intermittent forward movement of the workpieces as others in front are removed.

A further object of the invention is to provide such a conveying and storing unit wherein means are provided for advancing the workpieces slowly and intermittently along the unit in such a manner that they are not brought into violent contact with any part thereof during their travel therealong; and wherein, in one embodiment of the invention, means are provided for preventing any two workpieces coming into contact with one another throughout their travel along the unit. Thus we aim, among other things, to protect the workpieces from damage during their travel along the unit.

Having thus briefly and broadly stated some of the objects and advantages of the invention, we will now describe it in detail with the aid of the accompanying drawings, in which:

Figure 1 is a side elevation of the invention on a reduced scale, and

Figure 2 is a partial plan view on a larger scale.

Figure 3 is an enlarged side view showing portions of the invention, and

Figure 4 is a section on the line 4—4 of Figure 3.

Figure 5 is a diagrammatic view on a larger scale showing the operation of the yokes and movement of the workpieces.

Figure 6 is an enlarged view on the line 6—6 of Figure 1 showing the operation of the hydraulic valves.

Figure 7 is a wiring diagram, and

Figure 8 is a detail showing a slight modification.

Referring to the drawings, 1 designates legs arranged in laterally opposed pairs connected to one another by transverse braces 2. Welded or otherwise secured to and projecting above the legs 1 are vertical mountings 3 to support guide rails 4 which extend along opposite sides of the unit throughout its length. Pads 5 are secured to the inner sides of the legs 1, and fastened as by screws 6a to the inner sides of the pads are spaced, parallel members or plates 6 which extend throughout the length of the unit. Formed through each plate 6 adjacent its upper margin is a horizontal row of uniformly spaced openings 7 each of which is in transverse alignment with one of the openings through the other

plate. Thus the parts above described serve as a frame to support pins 8 one of which extends through each opening 7.

Mounted in longitudinally spaced relation against the outer face of each plate 6 and upon consecutive pairs of the pins 8 are track sections 9 all of which are identical and have openings formed therethrough adjacent opposite extremities through which the pins extend. Mounted also in longitudinally spaced relation to one another against the outer faces of the track sections 9, and in overlapping relation to the latter, are other track sections 10 which are identical to the sections 9. Each adjacent pair of pins 8 supports opposite extremities of a track section 9, or 10, and also the adjacent extremities of separate track sections 10, or 9. The openings through each track section are relatively so located that the upper longitudinal edges of all the track sections are parallel and extend forwardly and downwardly—that is each track section is downwardly inclined towards the right in Figures 3 and 5. Thus the rear extremity of each track section projects above the intermediate portion of the contiguous overlapping track section in transverse alignment with it, so that a workpiece A travelling downwardly and forwardly upon one opposed pair of track sections 9, or 10, is adapted to be stopped by the rear extremities of the overlapping sections 10, or 9, next in front. By means hereinafter described a workpiece A resting upon one opposed pair of track sections 9, or 10, and bearing against the rear extremities of the transversely aligned track sections 10, or 9, immediately in front is adapted to be elevated sufficiently to roll down onto the last named track sections upon which it then continues to travel forward.

Pivoted on the inner extremities of each transversely aligned pair of pins 8 are the opposite extremities of a yoke 11, each of which consists of substantially radial arms 11a connected at their outer extremities by a transverse bar 11b. In the present instance lugs 11c project laterally towards one another from the outer ends of the arms 11a and removably secured to the said lugs are the opposite ends of the transverse bar 11b. Thus if it is desired to handle workpieces of greater length the width of the yokes may be readily increased by the substitution of longer bars 11b, and at that time the transverse spacing between opposed legs 1 may also be increased by the removal of the braces 2 and substitution of others of greater length. Secured to each of the transverse bars 11b and projecting radially outward therefrom is a finger 12.

Spaced beneath the yokes 11 and extending transversely between the plates 6 by which their opposite extremities are supported are a plurality of shafts 14 around each of which laterally spaced bushings 13 are mounted. Supported for rotation on the bushings are rollers 15 having annular flanges extending around their opposite sides. Thus longitudinally aligned sets of rollers are provided upon which separate and parallel pushers 16 are mounted for reciprocation by means hereinafter described. Each pusher 16 extends through substantially the entire length of the conveyor and preferably consists of two parallel bars 16a held in spaced relation at uniform intervals therealong by bushings 17b on pins 17. The fingers 12 projecting from a predetermined number of consecutive yokes 11 are longitudinally aligned for engagement by consecutive pins 17 forming part of one pusher, and the fingers projecting from an equal number of the next consecutive yokes are longitudinally aligned for engagement by an equal number of pins 17 on the other pusher. The arrangement is preferably such that only relatively few consecutive yokes are moved by each pusher, though altogether each pusher imparts movement to one-half the total number of yokes.

The upper edge faces 18 of the radial arms 11a of each yoke are longitudinally somewhat V-shaped as may be clearly seen from Figures 3 and 5. When a yoke 11 is so turned about its axis that its finger 12 projects vertically downward then the rear portions 18a of its upper edge faces 18 are substantially parallel with and slightly beneath the upper margins of the track sections 9, or 10, in transverse alignment with them, and the front portions 18b of those upper edge faces are forwardly and upwardly inclined so that they project above the track sections in transverse alignment with them. Then a workpiece A is adapted to roll forward along the portions of the track sections 9, or 10, above and in transverse alignment with the rear portions of that yoke until the said workpiece strikes the raised rear extremities of the track sections 10, or 9, next in front as shown at B. There the workpiece remains until the yoke is moved pivotally about its axis so that the rear portions 18a of its upper edge faces assume a forwardly and downwardly inclined position 18a'. During movement to that position the rear portions 18a are also lifted so that the workpiece thereon is raised to C to roll down into and along the rear portions of the transversely aligned track sections 10, or 9, against which that workpiece had previously stopped. After travelling partway along those track sections 10, or 9, the workpiece is stopped by the rear of the arms 11a of the yoke next in front, as shown at A2 in Figures 3 and 5, if that yoke next in front has not by then returned to its vertical position. But if the yoke has already re-assumed its vertical position then the arms no longer obstruct forward movement of the workpiece and the latter continues its advance along the track sections 10, or 9, until it strikes the rear extremities B of the next transversely opposed pair of track sections 9, or 10.

The arrangement of the yokes 11 is such that while they are adapted to be moved to their downwardly and rearwardly inclined positions by movement to the left (Figure 3) of the pushers 16 and the pins 17, they all resume their upright positions as soon as they are free to do so due to the locations of their pivot axes.

At the front extremity, that is at the right hand end of Figure 3, a bumper 22 is secured at opposite extremities to the guide rails 4 and extends between the latter. Consequently when a workpiece rolls down the rear portions 18a' (which are then forwardly and downwardly inclined) of the front yoke 11 the bumper stops it and it remains above the front portions 18b of that yoke. Then the weight of the workpiece prevents the yoke from re-assuming its normal vertical position although the pin 17 by which it was moved to its inclined position is returned to its original starting position. The pins 17 engage the forward edges of their respective fingers 12 to pivot the elevating members 11, but do not by-pass or pass beneath such fingers. Thus the pins 17' are shown in the right-hand section of Fig. 3 in their original starting position after being reciprocated to pivot the yokes which are disposed rearwardly or to the left thereof as viewed in the drawing. The succeeding workpieces engage the yokes forwardly thereof to prevent further travel until the yokes they engage return to their original positions. As soon as the leading workpiece is removed, the leading yoke will return to its original position by gravity and then the remaining yokes in the set will successively return to their original positions, allowing the workpieces to successively advance one position along the track sections. In that way a supply of workpieces uniformly spaced from one another is maintained adjacent the front of the conveyor. Consequently the unit functions not only as a conveying means but also as a storing means and for automatically advancing workpieces to take the place of those removed from the front.

The length of the track sections 9 and 10 and the shape of the yoke arms 11a determine the spacing be-

tween adjacent workpieces, which should often be sufficient to maintain flanges or other enlargements A¹ upon adjacent workpieces apart at all times during movement of the conveyor.

From the foregoing it is evident that so long as a yoke remains in its downwardly and rearwardly inclined position a workpiece cannot pass over it from behind because then the rear portions 18a of the upper edge faces 18 of that yoke project upwardly above the track sections along which the workpiece would otherwise travel. If, therefore, a series of say five consecutive yokes 11 are simultaneously turned to their downwardly and rearwardly inclined positions by movement of one of the pushers 16, the leading workpiece will be elevated onto the track section forwardly thereof and will travel along such track section until stopped by the trailing edges of the next track section, the workpiece which previously occupied such position having been moved ahead by the previous operation of the other pusher 16. Each of the workpieces above the other four yokes in the series will be elevated by its yoke onto the track section immediately ahead and will travel therealong until it engages the upwardly projecting portions of the yoke immediately ahead of the yoke by which it was elevated, where it will remain until the yoke that it rests against is returned to its original position. As soon as the leading workpiece of the series has advanced beyond the yoke by which it was elevated, such yoke will return to its original position under the influence of gravity, whereupon the succeeding workpiece is free to advance until it engages the rear extremities of the next track section. This action continues until all of the workpieces in the series have advanced one position. The trailing yoke in the series and its track sections are thus emptied in order to receive the leading workpiece of the next series of workpieces which are advanced in the same manner by actuation of the other pusher 16.

Of course if all the workpieces had to be advanced in sequence throughout the entire length of the unit then operation of the latter would be objectionably slow for many purposes. However in this arrangement substantially one half the total number of yokes are moved by each pusher, and by arranging the yokes in series or sets of say five, and spacing adjacent sets from one another by similar sets actuated by the other pusher, the time required for moving workpieces on the yokes of all the sets actuated by either pusher is only substantially the same as that required for advancing the workpieces on all the yokes of any one set.

Suitably mounted on the unit is a conventional hydraulic pumping set including a tank 24, a motor 25 and a pump 26 driven thereby. Mounted also in any preferred manner on the unit are cylinders 27 and 27a having pistons therein from which rods 28 and 28a, respectively, project. The rods 28 and 28a are connected by pins 30 to flanges 29 and 29a, each of which extends downwardly from one of the pushers 16.

Each cylinder 27 or 27a is adapted to be connected to the pump 26 by a feed line 32 or 32a and to the tank 24 by a return line 33 or 33a, respectively. A solenoid valve 34 having a spring return is interposed in the lines 32 and 33 and normally retains the line 33 open and the line 32 closed, however when the solenoid 38 in the valve 34 is energized the line 32 is temporarily opened and the line 33 is then closed. A similar solenoid valve 34a having a spring return normally holds the line 33a open and the line 32a closed.

The pushers 16 may be alternately reciprocated at timed intervals in the following manner: When a switch 35 is closed a circuit relay 36 is energized. The latter is connected to a timer relay 37 through which the solenoids 38 and 38a forming parts of the valves 34 and 34a, respectively, are adapted first to open the feed line 32, or 32a, and subsequently to close the last mentioned line and open the return line 33, or 33a. The electrical cir-

cuit which controls actuation of the pushers 16 is therefore arranged so that each of the pushers completes its reciprocating movement before the other pusher is reciprocated. The timing relay 37 may be so designed as to initiate actuation of the pushers at appropriate intervals allowing sufficient time between reciprocation of the two pushers for all of the workpieces which are advanced by one pusher to move ahead onto the next forward track sections before the other pusher is actuated to advance the remaining sets of workpieces.

The construction of the unit is also such that its length may be readily increased by securing additional plates 6 thereto by straps 40. In which case the length of the pushers is correspondingly increased by attaching extensions 41 to them as by pins 17a.

In the modified arrangement shown in Figure 8, a plurality of uniformly spaced yokes 11f are pivoted as before on pins 8f which support track sections 9f and 10f at a forward and downward inclination. Each yoke 11f is again adapted to elevate a workpiece AA and discharge it in a forward direction as indicated by the arrow F. This form of construction may be employed for handling shafting or similar parts which are of uniform diameter and have no flanges or other enlargements thereon which necessitate the maintenance of spacing between adjacent workpieces. Moreover this form of construction is particularly adaptable for such workpieces in process of manufacture which are not liable to be damaged by coming into contact with one another during their travel.

While in the foregoing the preferred embodiments of the invention have been described and shown, it is understood that further alterations and modifications may be made thereto provided the said alterations and modifications fall within the scope of the appended claims.

What we claim is:

1. A conveying unit comprising a fixed workpiece supporting structure including a plurality of track sections, each track section having an article supporting surface inclined downwardly toward its forward end, the rear extremity of each track section projecting above the forward end of the track section immediately behind it to provide a stop for the workpiece traveling along the track section behind it, a plurality of elevating members movably mounted on said structure, means for moving said members in one direction to lift workpieces stopped against said rear extremities of said track sections and deposit them on the next forward track sections, said members being movable back to their original positions by gravity, each of said members when moved in said one direction having a portion thereof disposed in the path of the workpiece following the workpiece which it elevates to prevent movement of said following workpiece along its track section until said member returns to its original position under the influence of gravity, each said member being engaged by the workpiece it has elevated to prevent return movement of each member as long as the workpiece it has elevated is stopped against the next forward member, whereby said workpieces are advanced in succession along said track sections beginning with the leading workpiece.

2. A conveying unit comprising a supporting structure having an article supporting surface thereon, all portions of said supporting surface being inclined downwardly toward the forward end of said unit, a plurality of stop means spaced along the length of said supporting surface, each of said stop means projecting above that portion of the supporting surface immediately behind said stop means to provide a stop for the workpiece traveling along such portion of said surface, a plurality of elevating members movably mounted on said structure, means for actuating said members to lift workpieces stopped against said stop means and deposit them on the next forward portions of said supporting surface, said members being returnable to their original positions by gravity, each of

said members having a portion thereof movable into the path of the workpiece following the workpiece which it elevates to prevent movement of said following workpiece until said member returns to its original position under the influence of gravity, each said member having a portion thereof engaging the workpiece it has elevated to prevent return movement of each member as long as the workpiece it has elevated is stopped against the next forward member, whereby said workpieces are advanced in succession along said supporting surface beginning with the leading workpiece.

3. A conveying unit comprising a plurality of track sections, each track section having an article supporting surface inclined downwardly toward its forward end, the rear extremity of each track section projecting above the forward end of the track section immediately behind it to provide a stop for a workpiece traveling along the track section behind it, a plurality of pivoted elevating members, means for pivoting said members in one direction to lift workpieces stopped against said rear extremities of said track sections and deposit them on the next forward track sections, said members being pivotable in the opposite direction by gravity, each of said members when pivoted in said one direction having a portion thereof movable into the path of the workpiece following the workpiece which it elevates to prevent movement of said following workpiece until said member returns to its original position under the influence of gravity, each said member having a portion thereof engaging the underside of the workpiece it has elevated to prevent return movement of said member as long as such workpiece is stopped against the next forward of said members, whereby said workpieces are advanced in succession along said track sections beginning with the leading workpiece.

35. 4. A conveying unit comprising a frame, a fixed workpiece supporting structure comprising a plurality of track sections supported from said frame, each track section having an article supporting surface inclined downwardly toward its forward end, the rear extremity of each track section projecting above the forward end of the track section immediately behind it to provide a stop for the workpiece traveling along the track section behind it, an elevating member pivotally mounted on said frame at each said track section, means for pivoting said members to lift workpieces stopped against said rear extremities of said track sections onto the next forward track sections, said members being returned to their original positions by gravity, each of said members having a portion thereof movable into the path of the workpiece following the workpiece which it elevates to prevent movement of said following workpiece along its track section until said member returns to its original position under the influence of gravity, each said member engaging the workpiece it has elevated to prevent return movement of said member as long as such workpiece is stopped against the next forward of said members, whereby said workpieces are advanced in succession along said track sections as soon as the leading workpiece disengages its elevating member.

5. A conveying unit comprising a frame, a fixed workpiece supporting structure comprising a plurality of track sections supported from said frame, each track section having an article supporting surface inclined downwardly toward its forward end, the rear extremity of each track section projecting above the forward end of the track section immediately behind it to provide a stop for the workpiece traveling along the track section behind it, an elevating member mounted on said frame at each said track section, and means for actuating said members to lift workpieces stopped against said rear extremities of said track sections onto the next forward track sections, said actuating means comprising a plurality of independently operable means each of which is engageable with a plurality of longitudinally spaced sets of said elevating members, each said set of elevating members consisting of a plurality of consecutive elevating members.

6. A conveying unit according to claim 5 including means for effecting alternate operation of said actuating means.

7. A conveying unit comprising a frame, a plurality of track sections supported from said frame, each track section having an article supporting surface inclined downwardly toward its forward end, the rear extremity of each track section projecting above the forward end of the track section immediately behind it to provide a stop for the workpiece traveling along the track section behind it, elevating members movably mounted on said frame for lifting workpieces stopped against said rear extremities of said track sections onto the next forward track sections, and a plurality of independently operable actuating means for said elevating members, each of said actuating means being engageable with a plurality of longitudinally spaced sets of said elevating members, each said set comprising a plurality of consecutive elevating members.

8. A conveying unit comprising a frame, a plurality of track sections supported from said frame, each track section having an article supporting surface inclined downwardly toward its forward end, the rear extremity of each track section projecting above the forward end of the track section immediately behind it to provide a stop for the workpiece traveling along the track section behind it, an elevating member pivotally mounted on said frame at each said track section, means for pivoting said members to lift workpieces stopped against said rear extremities of said track sections onto the next forward

track sections, said members being returned to their original positions by gravity, each of said members having a portion thereof movable into the path of the workpiece following the workpiece which it elevates to prevent movement of said following workpiece along its track section until said member returns to its original position under the influence of gravity, each said member engaging the workpiece it has elevated to prevent return movement of each member until the next forward of said members has returned to its said original position, whereby said workpieces are advanced in succession along said track sections as soon as the leading workpiece disengages its elevating member, and a plurality of actuating means for pivoting said elevating members, each said actuating means being operable to pivot a plurality of spaced sets of elevating members, each said set comprising a number of consecutively disposed elevating members.
